FISHING LURE

William O. Crutchfield, Elizabethton, Tenn.
Application May 23, 1958, Serial No. 51,058

Term of patent 14 years

(Cl. D31—4)

Fig. 1

Fig. 2

The dominant features of my design reside in the full line portions of the drawing.

I claim:

The ornamental design for a fishing lure, as shown and described.
